Primary Examiner — Calvin E Vansant*Assistant Examiner* — Giang Hoang Tran(74) *Attorney, Agent, or Firm* — Luedeka Neely, P.C.(57) **CLAIM**

The ornamental design of a golf cart front body, as shown and described.

DESCRIPTION

FIG. 1 is a perspective view of the golf cart front body of our new design.

FIG. 2 is a front view thereof.

FIG. 3 is a rear view thereof.

FIG. 4 is a right side view thereof.

FIG. 5 is a left side thereof.

FIG. 6 is a top view thereof.

FIG. 7 is a bottom view thereof.

FIG. 8 is another perspective view thereof; and,

FIG. 9 is another right side view thereof.

The broken lines in the drawings are included for the purpose of illustrating unclaimed features and form no part of the claimed design.

1 Claim, 9 Drawing Sheets(56)
